SASH LOCK

Robert K. Unter, Roscoe, Ill., assignor to National Lock Co., Rockford, Ill., a corporation of Delaware

Filed Aug. 24, 1964, Ser. No. 81,412

Term of patent 14 years

(Cl. D10—11)

FIG. 1 is a plan view of a sash lock embodying my new design, the assembly being shown in locked position; FIG. 2 is a front elevational view thereof;

FIG. 3 is a side elevational view thereof;

FIG. 4 is a rear elevational view thereof;

FIG. 5 is a plan view of the sash lock in partially unlocked position; and

FIG. 6 is a plan view of the sash lock in completely unlocked position.

I claim:

The ornamental design for a sash lock, substantially as shown and described.
